[57] CLAIM

The ornamental design for a beverage dispensing tower, substantially as shown and described.

DESCRIPTION

FIG. 1 is a left rear perspective view of a beverage dispensing tower showing our new design;
FIG. 2 is a front elevational view thereof;
FIG. 3 is a left side elevational view thereof, the right side elevational view being substantially identical;
FIG. 4 is a top plan view thereof; and
FIG. 5 is a rear elevational view thereof.
